UNITED STATES PATENT OFFICE

FERDINAND FISCHER, OF BERLIN, GERMANY

LITHOGRAPHIC OR OFFSET PRINTING PLATE

Application filed December 16, 1929, Serial No. 414,570, and in Germany December 24, 1928.

Hitherto it has been customary, prior to applying the letters and the like, to grain the upper surface of lithographic printing plates and particularly of printing plates made of aluminum, by grinding, sand-blasting or chemical action, in order that pigments, ink, light-sensitive layers and other substances used in printing may adhere better to the plate.

These methods, however, have the disadvantage of not providing an entirely uniform surface. It has therefore been proposed to produce printing plates by the galvanic method, but the latter method shares with the former the common disadvantage of occupying considerable time.

In order to eliminate the disadvantages of these methods and to render the production of printing plates as economical as possible, according to the present invention, whilst utilizing an existing, previously prepared working mould, the surface grain is imparted to the printing plate by plastic moulding.

For example, the graining is imparted to the printing plate by a pressing or rolling impression of a grained working surface. A printing plate of mouldable material thus receives a surface grain effect dependent upon the grain of the working surface. The advantage of this method is as follows:—The graining of all printing plates produced with the same working surface is absolutely equal and if certain spheres of utility require another form of graining it is merely necessary to use another working surface.

The graining may also be effected, clearly defined locally, only on certain parts of the printing plate and the graining only takes a minimum amount of time and is much cheaper than all the methods hitherto customary. As working surface a level grained surface may be used which is applied by stamping or pressing, or a suitable roller may be used which rolls its grain on. The graining of the printing plate can be effected on one or both sides. The latter method is particularly adopted in the case of thin printing sheets of office machines (see German Patents 204,517 and 410,168), the graining being used to impart a better hold for the glue (or

size) of printing plates coated at the back with paper or the like. Instead of a pasted-on coating, similarly acting materials, such as celluloid, varnished surfaces and the like may also be applied to the grained rear side.

In the accompanying drawings, which illustrate two forms of my invention by way of example, Figs. 1 and 2 are respectively perspective views of different forms of the invention.

In Fig. 1, a long web or ribbon of extremely thin lithographic metal is shown at 1, together with a base plate or lower die 2. The upper die 3 is preferably provided with a "grained" or roughened surface 4. Now if the die 3 is depressed upon the web 1 periodically, grained surfaces 7 are formed upon the web 1. Obviously, if the lower die 2 is also provided with a grained or roughened surface, corresponding grained surfaces 7 will also be formed on the back face of the web 1.

Fig. 2 is almost identical with Fig. 1 except that the dies 2 and 3 are replaced by rollers 5 and 6.

What I claim is:—

1. In the manufacture of lithographic printing plates of moldable material, the step of graining the face and the back of the plate by a pressing action producing a large number of depressions simultaneously.

2. In the manufacture of lithographic printing plates of moldable material, the step of graining the face and the back of the plate by a pressing action producing a large number of depressions simultaneously and applying a coating to said grained back.

In testimony whereof I affix my signature.

FERDINAND FISCHER.
